DISPLAY SCREEN FOR TELEVISION TUBES

Craig S. Nunan, Palo Alto, Calif., assignor to Chromatic Television Laboratories, Inc., New York, N.Y., a corporation of California

Application December 29, 1955, Serial No. 556,338

13 Claims. (Cl. 315—14)

This invention relates to display screens for use in television cathode-ray tubes and particularly in display screens for use in tubes intended for the display of television images in color.

Among the objects of the invention are to provide display screens capable of giving color images having a high degree of saturation in the color displayed, to provide means for reducing the apparent size of the spot upon the screen produced by the impact of the cathode-ray beam, to provide means for reducing the intensity of "halos" surrounding the spot, and, generally, to provide tubes wherein the television image produced has a maximum degree of crispness, contrast, and color definition.

In cathode-ray tubes generally there are a number of causes which either increase the size of the spot of the light produced by the impact of the cathode-ray beam upon the display screen or produce halos of light around the spot so produced. One cause of such effects is the multiple reflection, from the surfaces of the glass base upon which the display screen is formed, of light emitted from phosphors in optical contact with the screen and at relatively large angles from the perpendicular to those surfaces. The intensity of this halo is reduced, in accordance with known practice, by tinting the screen; reflected light must then traverse the screen at least three times and at relatively high angles before it can reach the eyes of the viewer and its relative intensity, in comparison with unreflected light, is therefore greatly reduced.

A second source of halo, increase in spot size, and undesired increase in the general level of the illumination of the screen is secondary electrons emitted by the screen. Such electrons are emitted with only a few electron-volts energy, but they fall back against the screen and produce an over-all low level of illumination. It is also common practice to avoid this effect, and, at the same time, to increase the light reaching the eye of the viewer by depositing a reflecting layer of aluminum on the surface of the screen facing the electron source. It is customary to minimize the thickness of this conducting layer so that the loss in energy of the beam in penetrating it is minimized while the low energy secondary electrons thus emitted have not enough energy to penetrate the aluminum and reach the phosphors with sufficient energy to excite luminescence.

Several other sources of increase in spot size and halo are effective in color television tubes, which frequently have either a mask or an electron lens structure interposed between the source of the electron beam and the screen. The electrons striking the mask or electron lens structure may be scattered without material loss of energy, being effectively refracted at the edges of the apertures in the structure, or they may cause the emission of low energy secondaries which, particularly in the case of electron lens structures, may be accelerated between the structure and the screen and strike it with sufficient energy to penetrate the aluminum, as in the case of the primary beam, and excite luminescence. Finally, there are scattered electrons which emerge from the screen at consid-

2

erable angles from the perpendicular and with a large proportion of their initial energy. In monochrome television tubes, without a mask or lens structure, these electrons would normally reach the walls of the tube and do no harm. Where a mask or lens structure is present, however, they may be refracted back to the screen itself, and strike it with sufficient energy to penetrate the usual thin metallic film, causing a general increase in the level of background illumination displayed by the screen. Such electrons may strike the phosphors emissive of any of the primary colors used in the system, and therefore the light emitted by the scattered electrons will be whitish in overall effect. The result is a general desaturation of the colors displayed, so that even though the background level or D.C. component of the picture image may be proper, all of the colors may be paler than the original view.

It is the effect of these high energy scattered electrons which has proved in practice to be most difficult to overcome or minimize, and it is to the suppression of the effects of such electrons that this invention is particularly directed.

In using a film of aluminum over the phosphors of the display screen to provide a conducting surface, to reflect light emitted from the phosphors and to absorb the energy of secondary electrons, it has been the practice to make the film as thin as possible and still have it continuous, to provide a conducting mirror surface. Electrons penetrating a film of this kind suffer a loss of energy, almost all of the energy thus lost being expended in ionizing the penetrated material. This loss of energy causes a diminution in the light energy emitted by the phosphors; at least to a first approximation, the diminution in light emitted is proportional to the ionization loss of energy by the beam. The loss of energy is related to the density of the material which the beam penetrates, and the range of the beam—i.e., the distance which the beam will penetrate—into any material of relatively small atomic number, before all of its energy is lost, can be expressed by the approximate equation:

$$R = 2.1V^2 \quad (\text{Equation 1})$$

where R is in terms of micrograms per square centimeter of the material from which the film is formed and V is the kinetic energy of the electrons, expressed in kilovolts.

The films normally employed in metallizing television display screens are formed of a quantity of aluminum that would result in a thickness of film of about 1500 Angstroms, or 40 micrograms per square centimeter. This is about $\frac{1}{9}$ of the electron range in monochrome tubes operated at 13 to 14 kv. anode potential; it is from $\frac{1}{17}$ to $\frac{1}{21}$ of the range of 18 kv. to 20 kv. electrons. Such higher potentials are being increasingly used in color tubes, where the substantially same film thicknesses as for monochrome tubes has customarily been used.

The equation for electron range is based on the fact that electrons of the beam lose energy almost entirely through ionizing the material through which they pass. The density of materials of fairly low atomic number, Z , is approximately proportional to their atomic number, which is equal to the number of orbital electrons available to be ionized. The range given is along the actual path of the beam electrons, and these are repeatedly deflected or scattered, the scattering being attributable to the nuclear charge. The beam electrons therefore follow tortuous paths, and it comes out that except in the very thinnest films, in which few scattering events occur, the loss of energy by beam electrons passing through a film of fractional-range thickness is a nearly linear function of the film thickness. It is for this reason that it is the practice to make the films as thin as possible to obtain the maximum illumination from the tube.

In passing through very thin films the angles through which the electrons are scattered follow substantially a Gaussian distribution curve. In thicker films, and after entering the phosphor layer, the beam electrons are subjected to many scattering deflections through random angles, resulting in an angular distribution that is still a probability function but no longer follows the Gaussian law. In entering any material there will be some electrons which are subjected to single scattering, and are "reflected" without material loss of energy. Most of the electrons will be subject to multiple scattering, accompanied by a loss of energy due to multiple collisions. Eventually the scattering will be through a solid angle of 4π radians.

There is a possibility of electrons being "back-scattered," (meaning deflected through an angle that will result in their re-emergence from the face of the screen) at any depth of penetration in any material. The probability of such back-scattering is roughly proportional to Z .

The angular distribution of such back-scattered electrons is substantially independent of the scattering material. The number so back-scattered, however, is nearly directly proportional to Z , for the more deeply the electrons have penetrated before undergoing enough scattering deflections to reverse the general direction from their initial course the greater the probability of their losing their energy before they can re-emerge from the surface of the screen.

The effective Z of a compound in causing scattering is substantially the arithmetic mean of the atomic numbers of the atoms entering into it. Most phosphors are salts of heavy metals, many containing zinc, $Z=30$, or cadmium, $Z=48$ as a base. A frequently used blue phosphor is zinc sulfide, ZnS , with an effective Z of 23. In one color tube the average effective value of Z is 16.8, using the best phosphors, as regard color emitted, presently, available; in another the effective value of Z is 17.5.

In accordance with the present invention a phosphor screen is employed having the desired characteristics as to color emitted and pattern. Upon the phosphor screen there is deposited a coating of material of effective atomic number lower than that of the phosphors and of a thickness in terms of electron range R , several times that normally employed in the aluminum coatings, provided to give conduction and light-reflection. The thickness of this coating is preferably from $\frac{1}{6} R$ to $\frac{1}{3} R$, with an optimum of about $\frac{1}{5}$ of the range of electrons having the energy in electron volts for which the tube is designed, in which the screen is used leading, in a tube designed for 18 to 20 kv. beam energies, to films from 3 to 6 times as thick as those normally employed; preferably about 3.5 times normal thickness for an 18 kv. tube or 4.5 times normal thickness for a 20 kv. tube. Aluminum ($Z=13$) having an atomic number only slightly less than the average of the phosphor coatings, will give a materially increased ratio of total light to halo, with a consequent increase in picture contrast and color saturation; preferably, however, the material chosen for the coating is one from the first group of the periodic table; beryllium ($Z=4$) or boron ($Z=5$) being among the preferred materials.

The above will be more evident with a consideration of the accompanying drawings and the ensuing description thereof. In these drawings:

Fig. 1 is a diagrammatic illustration of a tube of the type to which this invention primarily relates;

Fig. 2 is a fragmentary cross-sectional view through the display screen and the focusing electrode structure of the tube of Fig. 1, illustrating the path of the primary electron beam as well as the electron and light paths which are responsible for the various halos, spreading of the light spot, and over-all raising of the background level which has been discussed above; and

Fig. 3 is a diagram of the face of the screen, illustrating

the areas impacted by the various electrons whose trajectories are shown in Fig. 1.

The tube of Fig. 1 is shown symbolically to illustrate the conditions giving rise to the particular problem which the present invention is designed to alleviate. Characteristically, a tube of this character will comprise an evacuated envelope 1, which is generally of funnel-shape and can be either metal or glass. For present purposes it will be assumed that this envelope is of metal; if of glass it will be provided with a conductive lining. The large end of the funnel is provided with a transparent window 3 through which the television images are displayed. In the neck of the funnel is an electron gun 5. Only one such gun is shown, although in certain forms of the tube for which the present invention is adapted a plurality of guns may be used.

Within the window 3 is the display screen 6 upon which the television images are projected. The screen comprises a transparent base 7, which may, in certain instances, 20 be the window itself. Deposited upon the surface of the screen which faces the electron gun is a layer 9 of phosphors which are deposited (for a color tube) in a repeating pattern of color cells which, in one dimension at least, are of the order of magnitude of a single "picture point" or elemental area of the image to be reproduced. These cells may be of like size in the other dimension, or they may be of strips extending entirely across the screen area. In the present instance it will be assumed that they are of this latter form. Each color cell includes sub-areas of the individual phosphors which upon 25 electron impact emit light of the various primary colors used in the system for which the tube is designed, usually red, green, and blue.

Deposited upon the layer of phosphors 9 is a film 11 which will be assumed for the present purposes to be of aluminum, although, as will be shown hereinafter, beryllium is even better. It is with this film that the present invention is particularly concerned and its characteristics will be described in detail later.

35 40 Mounted adjacent to this screen is a lens-grid or focus-grid structure 13, which, since a strip-type phosphor screen has been assumed, comprises a multiplicity of elongated linear electrodes, the interspaces between which form the apertures of the multiplicity of electron lenses 45 each of which is electron-optically aligned with a corresponding color cell on the screen. With a single gun tube, of the type shown, the electrodes forming the grid are divided into two sets which are mutually insulated and interleaved.

50 55 In the operation of the tube shown, the various elements within the tube are operated at definite relative potentials. This is symbolized in the drawing by conventionally shown potential source 15, connected across a voltage divider 17 which has various taps connected to these elements. The most negative point on the divider connects to a control grid 19 of the electron gun. The gun cathode 21 is connected to a slightly more positive point on the divider, the voltage with respect to the grid usually being somewhere in the neighborhood of 100 volts or less.

60 65 Taking the other elements of the tube in order of increasing positive potential, the lens grid 13 may be operated somewhere in the neighborhood of 5 kv. positive to the cathode, the gun anode 22 and the envelope of the tube somewhere in the neighborhood of 200-400 volts positive to the lens grid, and the film 11 about 18 kv. positive to the cathode or 13 kv. positive to the grid 13. It is to be understood that these figures are given for the purpose of illustration only, and that tubes may be designated to operate at relative voltages quite different from those here suggested. Furthermore, it will be realized that the lens-grid structure here shown is one of the simplest, and that, in addition to the single grid here described, a lens-grid can include one or more additional grids, which may be either nearer to or farther from the screen than that

forming the apertures of the electron lenses. In the present case the electron lenses are formed by the electric fields between the film 11 and the grid wires 13. In multiple-plane grid structures the focusing fields may be set up between the elements of the grid itself, in which case the film 11 need not necessarily be of conducting material, as far as focusing action is concerned.

With the particular form of lens here described, and with the relative voltages mentioned applied to the electrodes, a beam of cathode rays from the gun 5, directed through any of the apertures in the lens-grid structure, will be focused on the center of the corresponding color cell. So focused, its cross-sectional width, normal to the electrodes of the grid, will be small in comparison to the width of the aperture and the beam will fall on a particular phosphor; i.e., that which occupies the mid-position in the array of strips of different phosphors forming the cell. For various reasons which are not pertinent to the present invention the central phosphor strip will usually be that emitting green.

In order to change the color displayed by the tube, a potential difference is applied between the two sets of electrodes, 13_b and 13_r, of the grid. This potential difference may be applied from a "color oscillator" 23, connected across a resistor 25, the center tap of which connects to the voltage divider 17 so that the latter supplies the mean potential of the grid. The oscillating voltage thus applied deflects the electrons passing through the interspace between the electrodes to one side or the other, so that the beam is focused on either the red-or blue-emitting phosphor as the case may be, depending upon the phase of the voltage supplied by the oscillator 23.

In operation the tube is also provided with a conventional scanning yoke 27 which deflects the beam over the surface of the display screen in a raster which defines the picture area. There will usually also be provided means, not shown, for interrupting or blanking the beam as its focal point is deflected across the junction between the different phosphors as a result of the shifting position of the focal point effected by the oscillator 23.

If a television image is to be displayed on a tube of the character here described in natural-appearing colors, it is obvious that the various phosphors must be excited at such intensity and for such relative periods of time that the eye will integrate the light emitted by them to show both the proper hue and the proper degree of saturation. If, for example, it is desired to display a picture element in green, if any electrons from the beam fall on either the red-emitting or the blue-emitting phosphors there will be some color degradation; if the light excited from both phosphors is of equal energy the over-all effect will be that the primary-color green is diluted or desaturated, tending to produce a pastel shade instead of a saturated one. If the red phosphor is more efficient than the blue, the green will have a yellowish cast while if the blue is the more efficient the dilution will be bluish, tending to turn a pure green into a pale cyan.

What happens in a tube of conventional construction (having the usual minimum thickness aluminum layer) when a high energy beam such as is produced by the tube described strikes a phosphor coating is illustrated in Figs. 2 and 3. The primary beam from the electron gun, the center line of which is designated by the reference character 29, approaches the screen at an angle ϕ from the normal to the screen surface. The focused beam strikes the screen at the point designated as A in both Figs. 2 and 3. Shown as a short black line in Fig. 3, this illustrates the relative size, on a greatly exaggerated scale, of the particular color element the beam is intended to illuminate.

Light is radiated from those illuminated phosphors which are in optical contact with the screen in accordance with Lambert's law. Light emanating from the point A at relatively wide angles from the normal is refracted still

more widely as it passes through the front surface 31 of the screen base. Light emanating from beyond the critical angle is reflected from the front surface of the base back to the rear surface 33, where it is re-reflected, and probably scattered in part, to be visible probably as a halo, this effect being illustrated at B in Figs. 2 and 3.

In Fig. 3 the circle B marks the inner edge of this halo. This will be the brightest portion, the halo fading from this point outward due to the Lambert's law emission from the phosphors. The color of the halo will be the same as that emitted by the phosphor instantaneously impacted, but it will be constantly changing, as the spot A is deflected from phosphor to phosphor and as the beam is scanned over the surface of the screen. Therefore, except in the case of a large area of a single primary color, the effect of the halo will be to dilute the colors displayed and tend to raise the over-all level of the white background.

As the beam passes between the grid wires 13_b and 13_r, a small percentage will strike the conductors and cause the emission of low-velocity secondary electrons. These electrons, under the influence of the perhaps 13 kv. field between the grid and the film 11, will fall directly to the screen, exciting illumination from the points designated as C in Figs. 2 and 3. Again it will be seen that the effect will be a general dilution of the color displayed, for it is evident, as shown in Fig. 3 particularly, that the phosphors occupying these points have no constant relationship, effective throughout the screen, to the phosphor at point A. The color of this dilution will vary from point to point, over the surface of the screen, due to the relative displacement of the various phosphors with respect to the location of their corresponding apertures and to the angle of incidence at the beam.

In addition to the low velocity secondaries causing the effects described at C, a certain percentage will be scattered and emerge from the grid conductors at fairly high velocity and at random angles to the beam path. These electrons, too, will be accelerated by the field between the grid and the screen, and will follow parabolic courses, exciting illumination in semi-lunar areas designated as D in Fig. 3. Since, in a practical tube, the total physical area of the grid conductors will be only somewhere in the neighborhood of 20% of the screen area and their effective area is even less, and since only a relatively small proportion of the electrons which do strike the grid conductors will be scattered at high energy, the illumination from the electrons forming the areas D is not as important as some of the other sources which have been mentioned.

The final source of color dilution, and the one which has proved most troublesome in practice, is the result of relatively high-velocity scattered electrons from the screen itself. The electrons reaching the screen have an energy which is proportional to the voltage through which they have fallen between the cathode of the gun and the screen. The back-scattered electrons may emerge from the screen at any angle and with any energy up to substantially that of the incident beam. Experimentally it has been shown that the distribution in angle is substantially independent of the material doing the scattering. With a perpendicularly incident beam it is clear that the electrons must be deflected through a total cumulative angle of over 90° in order to emerge. The distribution in angle of the emergent electrons rises from substantially zero at 90° to a maximum at 104°, falls to less than 20% of maximum at 120°, and then falls off nearly linearly, approaching zero again at 180°.

The energy distribution in the back-scattered electrons also varies. The maximum energy increases from near zero at 90° to a maximum in the region from 103° to 113°, and finally decreases approximately linearly.

Fig. 2 illustrates a number of possible trajectories of the scattered, high-energy electrons. Certain of these electrons, of maximum energy and scattered through wide

angles, will penetrate the grid and enter the space between it and the electron gun, as is illustrated by the trajectory 35. Once they have done so they will be attracted to the wall of the envelope instead of returning to the screen. An electron of equal energy, but scattered through an angle slightly lower than that which would cause it to follow trajectory 35, so that its component of energy normal to the screen is less than the screen-to-grid voltage, will be refracted along a path substantially as is indicated by the trajectory 37 and fall back to the screen with an energy and at an angle to the screen surface substantially equal to that at which it emerged, although its component of energy normal to the screen will be equal, in the limit, to the grid-screen voltage. Still more electrons, scattered through smaller and smaller angles, will have trajectories such as are illustrated by the curves designated by the reference characters 38 and 39. Such electrons will fall in the area generally designated at E of Fig. 2 and within the boundary represented by the circle E of Fig. 3. Electrons emitted from deeper within the screen structure penetrated by the beam, at any of these various angles, will emerge with lower energy, and may impact the screen at any point within the circle E. The outer limit of this circle is defined by maximum energy electrons emitted at a 45° angle to the normal to the screen. The region within which they impact the screen is therefore independent of the angle ψ , but their concentration will vary with this angle, being greatest in azimuths opposite to that of the entering beam.

As has been indicated above, any practical display tube for television purposes must be designed to operate within a very limited range of voltages. If this range is exceeded in use, insulation breaks down, flash-over occurs, and the life of the tube is shortened below practical limits. If operated at materially lower voltages, the brilliancy of the image falls off so rapidly as to become unacceptable to the public. The energy of the electron beam and, therefore, its range in any of the materials which are employed in the construction of display screens, is therefore a fundamental design parameter of any tube which can be commercially marketed.

It has also been pointed out that in order to provide screens of maximum brilliancy it is accepted practice to make the aluminum layer 11, when used, as thin as possible and still secure continuity and thus provide a mirror surface; i.e., its thickness has been "minimized."

In accordance with the present invention the layer 11, instead of being "minimized" is "maximized"; its thickness is so proportioned that substantially all of the electrons which are back-scattered from the phosphor surface have their remaining energy absorbed in the layer 11 in passing back through it twice before they can again reach the screen to cause halo. On its face, this would appear to mean that the thickness of the film should be equal to one-third of the range of the beam electrons, but actually this is neither necessary nor desirable. Both theory and practice show that by far the greater number of the back-scattered electrons have been subjected to many scattering deflections before they emerge and have therefore traversed paths longer than the actual thickness of the film. Excess film thickness causes unnecessary loss of illumination, and hence it has been found that in practice the optimum thickness of the film is from $\frac{1}{6}$ to $\frac{1}{5}$ of the theoretical range. As already stated of electrons back-scattered from the phosphors, the maximum of both energy and number occurs in the neighborhood of 104°, which corresponds to an angle of 14° to the surface. Such electrons, assuming no further scattering in the layer 11, would have to traverse a path equal to substantially the entire range of the electrons in their three passages through the layer even if the thickness is only $\frac{1}{6}$ R. Actually, of course, they are subject to further scattering in the layer, more and more as their velocity decreases and therefore, so far

as scattering by the phosphors is concerned, such film thicknesses are substantially as effective for suppressing halo as thicker films would be.

Although, as has been mentioned, some scattering occurs from the first penetration of the electrons and with any material, the probability of scattering and the angles through which it occurs varies inversely as the electron energy. The deeper the electrons penetrate into layer 11 and the phosphors underlying it the greater will be the probability of back-scattering and the greater the probable angle through which they are deflected in each scattering event. With high voltage tubes such as are used for color reproduction, relatively little scattering occurs while the rays are penetrating through the first quarter or so of their range, most of it being effected when the electrons have penetrated into the phosphor layer itself. It is for this reason that an aluminum layer of $\frac{1}{6}$ R or more will cut down the effective halo materially; to a much greater extent than the difference between its atomic number Z and the effective Z of the phosphors would indicate. If, however, the Z of the overlying layer were equal to or greater than the effective Z of the phosphors the total scattering would be the same as though the layer were omitted and although it would be only those scattered in the upper portions of the layer that would reach the screen the loss of primary illumination would be such that little relative improvement in color saturation would be obtained.

Because some scattering does occur in the overlying layer, however, it is preferable to make this layer of as low Z material as possible, consistent with the processing which the tube must undergo in construction. For this reason materials having a lower atomic number give even better results than an aluminum coating. Thus if the layer 11 is formed of beryllium the number of electrons back-scattered by the layer itself will be reduced substantially in the ratio of the atomic number of beryllium to that of aluminum or to a little more than a quarter of the number back-scattered by aluminum. This results in a further decrease in the ratio of halo intensity to intensity to illumination. It will be apparent that the few electrons which are back-scattered by the protective layer will have traversed a smaller proportion of their total range than those penetrating deeper and will therefore have more energy upon emergence from the layer and excite more halo. Therefore, while a layer of a given mass per square centimeter will be almost equally effective in suppressing halo due to back-scattering by the phosphors irrespective of its atomic number, lower Z materials will reduce halo resulting from back-scattering in the protective layer itself.

The reduction through the use of low Z materials, in average scattering angle of electrons which reach the phosphor layer is just as important, as the reduction in back-scattering in the layer itself. This reduction implies that even though a certain percentage of the beam electrons will be back-scattered in the phosphors they will have to be deflected to wider angles before this occurs and therefore, on the average, have to be subjected to more scattering deflections and traverse greater lengths of path within the phosphor itself, accomplishing more ionizing events within the phosphor, with greater consequent light emission. With the same proportional thickness of layer, in terms of electron range, their average energy on entering the phosphors will be the same, but because of their narrower dispersion in angle they will, on the average, have to suffer more scattering events before they are back-deflected widely enough to cause them to re-enter the overlying layer, penetrate it, and escape into the space above. Once having entered this space they are subjected to the field which accelerates them back toward the display screen, to re-enter it with the same velocity they had when they escaped.

As has been pointed out, the beam loses energy substantially in proportion to the depth to which it has pene-

trated and the probability of scattering to a given angle is approximately proportional to Z . With a coating of a lower effective Z than the average of the phosphors and of a thickness of $\frac{1}{6} R$ to $\frac{1}{5} R$ it is therefore quite apparent that most of the back-scattering must take place in the phosphor layer and that in this layer the electrons must be back-scattered far enough to leave it if they are to re-enter the layer 11 and escape through it.

It has also been mentioned that the greatest density of back-scattered electrons occurs at an angle of about 104° and that the peak in energy of such electrons occurs between 103° and 113° , roughly at the angle of maximum density. A thickness of $\frac{1}{6} R$ is just about sufficient to stop all electrons leaving the phosphors at peak energy and density, assuming no further scattering occurs in the layer 11 and that the sole effect of this layer is to absorb their energy. This assumption, of course, is not true; further scattering, with consequent increase in path length, occurs in layer 11 and therefore thinner layers, down to about $\frac{1}{6} R$, are quite effective.

Because, however, some of the scattering that occurs in the third traversal of the layer 11 is in a direction toward the phosphors, neither a layer of $\frac{1}{6} R$ nor $\frac{1}{5} R$ will completely prevent electrons from re-entering the phosphors. Not even a layer of the theoretical thickness of $\frac{1}{3} R$, which would require that all electrons reaching the phosphors would have to traverse the complete electron range to reach them again, will do this, since some very small proportion of the beam will be back-scattered in the outer portion of the layer 11 and thus retain enough energy to penetrate it upon their return to the screen. The maximum theoretical thickness of $\frac{1}{3} R$ therefore results in a loss in illumination which is not usually justified by the reduction in halo. Layers of $\frac{1}{6} R$ to $\frac{1}{5} R$ in thickness have proved to be the best compromise. Such layers reduce the relative brilliance of the halos which are formed by a large factor, much greater than the proportional loss in screen illumination.

As has been pointed out, both the energy and the density of the back-scattered electrons fall off rapidly beyond the peak angle of about 104° and it therefore comes out that the layer thickness which is sufficient to stop electrons of maximum energy and greatest number is also effective in stopping those scattered by the phosphors through greater angles.

There are several criteria which may be used in choosing the material for the layer 11. Preferably, of course, it will be one which will form a mirror surface to reflect light back out of the screen to increase its apparent luminance. Preferably, also, it will be a material of as low an effective atomic number as possible and this combination of properties indicates beryllium as first choice. Other factors which enter from a practical point of view are cost and complexity of apparatus required for depositing the layer upon the screen and since beryllium fumes are highly toxic, manufacturing precautions are necessary where it is used that are not required if non-toxic substances are employed.

Since the total number of back-scattered electrons is roughly proportional to the effective Z of the material penetrated by the beam and therefore some halo reduction can be attained by the use of any material having a lower Z than the phosphor layer. A large part of the effective Z of the phosphors commonly employed is due to the heavy-metal atoms entering into their composition, even though such atoms may form a minority of the total number entering into the compounds used. The phosphors mentioned above are characteristic, and it will be noted that taken over the entire screen their effective Z is something over half of the atomic number of the heavy-metal atoms entering into them. The total number of electrons scattered from near the outer surface of the layer 11 and which, therefore, retain enough energy to penetrate it when returned by the accelerating field, will therefore be decreased by any layer having an

effective Z less than one-half of the Z of the heavy-metal constituent of the phosphor. This can be taken as a rule-of-thumb criterion of the materials which will give a definite improvement. A more accurate criterion is

- 5 that the material chosen should have an effective Z lower than the average of the phosphors, considered over the entire screen. Any material meeting these criteria will give a reduction in halo below those in evidence where layers of conventional thickness and materials are used.
- 10 For best results, however, materials having the lowest possible Z should be employed.

It should be evident that the phenomena which the present invention prevents do not generally occur in screens used for the presentation of pictures in monochrome.

- 15 The aluminum films employed in such tubes serve to reflect the light emitted by the phosphor and to block negative ions from reaching the phosphor. Any film thick enough to form a conductive mirror over the phosphors will suffice to stop true secondary electrons, 20 emitted with an energy of only a few electron volts and falling back to the screen with the same maximum energy, and due to the very short range of negative ions will also block them and prevent the formation of an "ion spot" on the screen. In tubes which do not have 25 a powerful field in the neighborhood of the screen, tending to return higher velocity electrons to it, the great majority of scattered electrons escape and are collected by the conducting walls of the tube. It is therefore only 30 in tubes employing electrode structures adjacent to the screen that halos of the type suppressed by the present invention occur to any material extent.

Numerous types of electron lens systems have been suggested for use in tubes intended for the projection of television images in color, and as has been set forth above 35 various materials may be used which will give a material suppression of halos resulting from back-scattered electrons. The particular structures and materials shown in the drawings and discussed in the specification are therefore to be considered as merely illustrative, not as limiting the scope of the invention, all intended limitations being specifically expressed in the following claims.

What is claimed is:

1. In a cathode-ray tube including means for developing a beam of electrons having a maximum kinetic energy 45 of V kilo electron volts against a target area, said means including an electrode structure positioned generally in the path of said beam toward said target area and adapted for operation at a potential less than V with respect to the source of said electron beam, a display screen disposed in said target area comprising a transparent base, a phosphor coating comprising an element of relatively high atomic number covering said base, and a layer deposited over said coating of a material all components whereof have an atomic number less than one-half that 55 of said element and having a thickness corresponding to at least a mass per square centimeter of $0.35V^2$ micrograms.

2. A display screen in accordance with claim 1 wherein said layer is formed of a material all components 60 whereof have atomic numbers less than 14.

3. In a cathode-ray tube including means for developing a beam of electrons having a maximum kinetic energy of V kilo electron volts against a target area, said means including an electrode structure positioned generally in the path of said beam toward said target area adapted for operation at a potential less than V with respect to the source of said electron beam, a display screen disposed in said target area comprising a transparent base, a phosphor coating comprising an element of relatively high atomic number covering said base and a metallic layer deposited over said coating of a material all components whereof have an atomic number less than 14 65 and of a mass per square centimeter of at least $0.35V^2$ micrograms.

4. A display screen as defined in claim 3 wherein said metallic layer is formed of beryllium.

5. A display screen as defined in claim 3 wherein said metallic layer is formed of aluminum.

6. In a cathode-ray tube including means for developing a beam of electrons having a maximum kinetic energy of V kilo electron volts against a target area, said means including an electrode structure positioned generally in the path of said beam toward said target area adapted for operation at a potential less than V with respect to the source of said electron beam, a display screen disposed in said target area comprising a transparent base, a phosphor coating comprising an element of relatively high atomic number covering said base and a layer deposited over said coating of a material all components whereof have an atomic number less than one-half that of said element and of an average thickness of between $\frac{1}{6}$ and $\frac{1}{3}$ the range of electrons of V kilo electron volts energy, said range being defined as a thickness corresponding to a mass of $2.1V^2$ micrograms per square centimeter.

7. A display screen in accordance with claim 6 wherein said layer is formed of beryllium.

8. A display screen in accordance with claim 6 wherein said layer is formed of aluminum.

9. In a cathode-ray tube which comprises means for developing a beam of cathode rays of known maximum kinetic energy and structure within said tube which is subjected to electron bombardment by said beam and the composition of which includes elements of relatively high atomic number, the said structure including a luminescent screen, means for suppressing luminescence from said screen resulting from electrons of said beam scattered by said elements of the structure which comprises a deposit of material thereover each component whereof has an atomic number less than one-half that of the scattering element covered thereby and of an aggregate mass per square centimeter of at least 0.35^2 micrograms, where V is said known maximum kinetic energy expressed in kilo electron volts.

5 10. In a cathode-ray display tube which includes means for directing a beam of electrons of known maximum kinetic energy to impact a target area and structure adjacent to said area normally operative at a potential relative to the source of the electrons of said beam which is materially less than that necessary to impact such maximum kinetic energy to said electrons a display screen mounted within said target area comprising a light-transmitting base, a coating of phosphors on said base, the 10 average value of the atomic numbers of the atoms constituting said phosphors being Z , and a layer of material covering said coating having an effective value of atomic number which is less than 90% of Z and having a mass per square centimeter of at least $0.35V^2$ micrograms, where V is said maximum kinetic energy in kilo electron volts.

15 11. A display screen as defined in claim 10 wherein said layer of material is metallic.

20 12. A display screen as defined in claim 10 wherein the thickness of said layer of material is less than $0.7V^2$.

25 13. A display screen adapted for use in cathode-ray tubes wherein there is developed an electron beam of known maximum kinetic energy comprising a light-permeable base, a phosphor coating on said base, and a metallic layer overlying said coating and of a thickness corresponding to from $\frac{1}{6}$ to $\frac{1}{3}$ of the range of electrons of said known kinetic energy in the material of said metallic layer, said range being taken as equal to a thickness having a mass per square centimeter of $2.1V^2$, where V is said maximum kinetic energy in kilo electron volts.
